(57) **CLAIM**

The ornamental design of an adjuster wheel sensor bracket, as shown and described.

DESCRIPTION

FIG. 1 is a left side perspective view of the adjuster wheel sensor bracket of the instant invention;

FIG. 2 is a left side view of FIG. 1;

FIG. 3 is a right side view of FIG. 1;

FIG. 4 is a right side perspective view of FIG. 1; and,

FIG. 5 is a top plan view, the bottom forming a mirror image of the top.
